UNITED STATES PATENT OFFICE.

JOSEPH HOMER, OF NEW YORK, N. Y.

DENTAL RELATOR.

Application filed July 13, 1925. Serial No. 43,366.

This invention relates to a dental relator.

An object of the invention is to provide a simple and efficient device whereby the movable jaw may be connected to the main frame and caused, in the normal operation of the device, to move in a manner simulating the movement of the jaws of the person for whom a new set of teeth is being made.

A further object is to provide an improvement on my Patent No. 1,464,474, issued August 7, 1923, entitled Dental relator.

A further object is to provide a simple and efficient metallic lining for the plastic bearing member referred to in the above mentioned patent, so that in the operation of the jaws the pivot points will slide on metal and not on the plastic composition.

A further object concerns the provision of a frame which is supported at three points and is adapted for movement at each of these points.

A further object is to provide a frame which is provided adjacent the three points of support with adjusting screws to limit the movement in certain directions.

A still further object is to provide a frame so formed as to permit the operator an unobstructed view of and access to the moulds on the frame.

The invention is illustrated in figures, of which—

Figure 1 is a plan view of the device;

Figure 2 is a section taken on the line 2—2 of Figure 1;

Figure 3 is a plan view of the upper cup;

Figure 4 is a section taken on the line 4—4 of Figure 2;

Figure 5 is a section taken on the line 5—5 of Figure 1;

Figure 6 is a perspective view of one of the lining plates;

Figure 7 is a sectional view taken through one of the main bearing cups with a modified form therein;

Figure 8 is a perspective view of the lining used in Figure 7;

Figure 9 is a section of the portion shown in Figure 7 taken in a plane at right angles thereto;

Figure 10 is a perspective view of a slightly modified form of lining plate to that shown in Figure 6.

In its general aspect, the invention comprises a main frame on which the lower member of a pair of moulds for forming a new set of teeth is mounted. On this main

frame at the rear are provided two posts on the upper ends of which are bearing cups in which is disposed plastic material. In accordance with the previously mentioned patent of mine, this plastic material is adapted to receive the pivot members of the movable frame carrying the upper jaw member.

In accordance with the improvement, I dispose within the plastic material the metallic plates or sleeves formed in any desired manner, the pivot members of the movable frame adapted to bear on and slide in contact with such plates rather than moving directly in contact with the plastic material.

This eliminates the wear on the plastic material and preserves the form of the groove therein and also requires less skill on the part of the operator. A further feature comprises providing an additional cup containing plastic material and metal linings at the front of the main frame but at a much higher level than the level of the two jaw members and providing a portion of the movable frame with a pivot member to rest in this upper cup.

Thus, the movable frame is pivotally connected to the main frame at three points. The movable frame is provided with adjusting screws adjacent the pivot point so that movement downward beyond a certain point is prevented.

As shown in the drawings, the preferred form of the invention comprises a frame having a base plate 10 and two pedestal posts, one of which is shown in Figure 2 and designated by the numeral 11. At the top of these posts are disposed bearing cups 12 and 13. Within these cups are disposed masses of plastic material 14 and 15. In this plastic material are disposed metal lining plates 16 and 17. The form of the plates shown in Figures 1, 2, 5 and 6 is one preferred form.

Slidable on these plates within the mass of plastic material are the pivot condyles 18 and 19 of a movable frame member 20. This movable frame member stands forward to form an upper movable plate 21 adapted to support the upper mould or jaw 22, the lower one 23 of which is mounted on the plate 10. At the forward end of the upper plate 21, I provide a vertical extension arm 24 which extends upwardly and forwardly and is provided with a pivot member 25 adapted to depend into a cup 26 filled with plastic material 27 in a metal lining plate 28, this cup being mounted on the upper forward end of an arm 29

which rises from one of the pedestal posts 11. The movable frame 20 is provided with set screws 30 and 31 adjacent the pivot members 18 and 19. These set screws are adapted to be adjusted with reference to bearing surfaces, one of which is indicated in dotted lines in Figure 2 and designated by the numeral 32. These bearing surfaces are connected to the main frame and form extensions of the respective pedestal posts 11. The lower ends of the set screws are adapted to bear on these surfaces to limit the movement of the rear end of the frame 20. A set screw 33 is mounted on 24 and bears on the upper surface of the cup 26 to limit the downward movement of the pivot member 25.

As shown in Figures 7, 8 and 9, I may provide a different lining for the plastic material in the cups. In these figures, the lining is shown in the form of an open ended cylinder such as 34, into which the pivot end of the movable frame extends. If desired, cylinder 34 could be closed at one end without departing from the spirit of the invention. The shape of these linings or sleeves in the plastic material is designed to permit a path of movement to the above members of the movable frame approximately equivalent to the normal path of movement desired of the jaws.

In the operation of the device, the dentist, knowing the general character of the jaw movement under treatment, selects the desired linings and then inserts these linings in the plastic mass, after which the pivot members are brought into contact with the linings and manipulated until the lining has assumed in the plastic mass the desired relative position, so that as the movable jaw member is moved back and forth, the resulting movement will be as nearly as possible that desired of the jaws. The fact that the pivot members are sliding on metal surfaces will give a more positive, easy movement and will prevent wear on the plastic material. The fact that the movable frame is provided with supports at three points will also permit a more efficient, simple movement and require less skill on the part of the operator. Provision of set screws adjacent the pivot point will permit of the proper limitations being put upon the movement and will also permit of a very accurate aligning of the movable frame so as to properly register the upper jaw with respect to the lower jaw.

It is desirable to hold the large moulds, such as 22 and 23, on their respective plates by providing pins, such as 35 and 36, stuck into the jaw members and then passing an elastic band 37 over the rear face of the plates to which the jaw members are attached, so as to hold the jaw members in position.

65 Preferably the members 16, 17 and 28 are

made of stiff or rigid metal, such as aluminum or bronze but if desired, may be made of pliable or soft metal, such as tin foil or an alloy of lead. In regard to the lining 31, the same may be open at both ends as shown in Figure 8 or may be closed as shown at 34' in Figure 9. Also the bottom of the lining 34' may be tapered instead of flat if preferred. These linings, as for instance, lining 16, is shown as formed to permit a straight movement of the upper frame but if desired, they could be formed round as shown at 18' in Figure 10 whereby a curved structure is presented adapted to permit a movement in a curve which may be an arc of a circle or some other curve, so as to permit movements more nearly equivalent to natural jaw movements. It will also be evident that the condyles 18 and 19 may have tapered ends to receive a face bow or they may be made oval or round. It will also be understood that other modified structures or forms might be used without in any way departing from the spirit of the invention.

What I claim as my invention is:

1. In a dental relator a fixed frame, a movable frame, said movable frame having a pair of pivot members at the rear thereof mounted in a plane above the teeth of jaws carried by the fixed frame, said movable frame also having a pivot member disposed forwardly and at a substantially higher level than the rear pivot members, and bearing members carried by the fixed frame correspondingly disposed thereon to co-operate with the pivot members of the movable frame, the two rear bearing members being appreciably higher than the teeth mounted on said stationary frame and formed as pockets open at the top and one side while the forward bearing member is disposed above the rear bearing members and is formed open at the top, and a guiding lining member positioned in each socket adapted to guide said pivot members as they swing and as they move back and forth during the functioning of the movable frame whereby jaws mounted on the respective frames can be examined and observed and manipulated from the front of the device without difficulty.

2. In a dental relator a fixed frame having a base and a pair of posts, each of the posts having at the upper end a pocket open at the top and one side, the open sides facing each other, an arm extending from one of said posts formed with a socket open at the top, said socket being spaced substantially an equal distance from the other two sockets, a movable frame having a pivot member arranged in each of said sockets, and independently adjusted means arranged adjacent each socket for accurately aligning the movable frame in respect to the stationary frame.
